UNITED STATES PATENT OFFICE.

OWEN DAVID LUCAS, OF BAYSWATER, LONDON, ENGLAND, ASSIGNOR TO V. M. L.
EXPERIMENTAL LIMITED, OF WESTMINSTER, LONDON, ENGLAND.

SHELL FUSE.

1,415,593.

Specification of Letters Patent. Patented May 9, 1922.

Application filed February 16, 1922. Serial No. 536,858.

To all whom it may concern:

Be it known that I, OWEN DAVID LUCAS, a subject of the King of Great Britain, residing at 49 Linden Gardens, Bayswater, in the county of London, England, have invented certain new and useful Improvements in Shell Fuses, of which the following is a specification.

This invention relates to sensitive shell fuses of the type provided with a striker piston acted upon by the pressure of air during the flight of the shell to move the striker into sensitive position.

According to this invention both the striker and the detonator pellet are provided with piston surfaces adapted to be acted on by air pressure due to the flight of the shell and to move forwardly under such pressure into position for firing on impact. The fuse in this condition being sensitive so that the striker operates on the nose of the fuse meeting any obstruction which reduces the air pressure behind the forward piston. The striker and pellet are both held in the rearward position prior to discharge of the shell from the gun and on discharge are released to allow, during flight, the front member (usually the striker) to move forward first, the rear member following up under the action of the air pressure.

In order that the said invention may be clearly understood and readily carried into effect, the same will now be described more fully with reference to the accompanying drawing, which shows in longitudinal section a sensitive fuse embodying this invention, the fuse being fitted to a delay action or fixed time fuse ensuring explosion of the shell at the end of a predetermined interval in case the sensitive fuse has not acted.

A is the fuse body. B is the striker screwed into the striker piston B'. C is the detonator pellet with piston C'. Both pistons B' and C' being situated at the rear of their respective fuse members. D is a set back pin for the striker, the pin having a slightly conical end d acting against a ball d' adapted to bear against the bevelled edge b of the striker piston B', the set back pin being held up by a shearing pin d². D is a set back pin adapted to hold the pellet C in safety position through the centrifugal pin d³, the pin D' being held normally by the shearing pin d⁴. E is the fixed time fuse body carrying the magazine F and provided

with the fixed striker G and detonator pellet G' secured by a safety pin at g and when released by the safety pin held in a forward position by the spring g', a fuse composition coil f of ordinary type leading to the charge 60 f' in the magazine F.

The striker B is of hollow or tubular form and is provided with the head b' of mushroom shape, following the contour of the nose of the fuse body when in normal position and perforated at b² with a number of holes which reduce the area subjected to air pressure during flight. The striker is carried in the plug a screwed in the end of the fuse body A.

The firing pin b³ projects from the rear end of the striker into the detonator chamber H, in front of which is the cylinder J within which the striker piston B' lies, the pellet piston C' lying in the rear cylinder 75 H' at the back of the chamber H. The cylinder J is shown of somewhat larger diameter than the cylinder H', which in its turn is substantially larger in diameter than the detonator chamber H. The set back pins D 80 and B' lie in the longitudinal passages a' and a² of the body A and when the set back pin D' moves rearwardly on discharge of the shell and opens up the forward portion of the passage a² communication is afforded 85

between the cylinder J and the rear end of the cylinder H', behind the pellet piston C', through the small passage a³ leading from the cylinder J into the passage a² and the hole a⁴ leading from the passage a² into 90 the rear end of the cylinder H'. Both the cylinders H' and J are open to the atmosphere in front of the pistons B' and C' through the holes h and j leading into the external annular grooves a⁵ and a⁶ in the 95 body A, these grooves being directed backwardly so that the flight of the shell through the air causes suction in the holes h and j and consequently also in the cylinders H' and J, which assists in moving forward the 100 pistons B' and C'.

On discharging the shell from the gun the initial action is to release the set back pins D and D', the inertia of which breaks through the shearing pins d² and d⁴, the 105 pins D and D' flying into the rear ends of the passages a', a². When the pin D flies back the ball d' is released and the striker piston B' is free to move forward. The air pressure during flight acts on the 110

heads b' of the striker, but the area of the piston B' is substantially greater than that of the head owing to the holes b^2 provided in the latter. The air pressure transmitted 5 through the hollow striker and the air holes b^4 into the detonator chamber H and behind the piston B', acting in conjunction with the suction in front of the said piston through the suction holes j , moves the piston and 10 striker forward into the position shown in dotted lines. A small leakage hole b^5 is formed in the striker piston B', allowing air to leak from the back of the piston to the front, where there is reduced pressure. 15 This leakage hole serves to regulate the speed at which the striker moves forward and assists in maintaining it in a highly sensitive condition when in the forward position, the suction holes j drawing a stream 20 of air continuously through the cylinder J and the leakage hole b^5 . In this position the striker pin b^3 is displaced to the forward end of the pellet chamber H.

The release of the detonator pellet is practically simultaneous with that of the striker, 25 the set back pin D' on its rearward movement releasing the centrifugal pin d^3 which immediately flies out so that its conical end, which in safety position lies over the 30 bevelled forward edge of the pellet C, is withdrawn and the pellet C is therefore free to move forward. The set back of the pin D' opens the passage a^2 and communication 35 is established between the rear end of the cylinder J and the back of the cylinder H' as already described, so that air pressure in the cylinder H' is allowed to act on the back of the pellet piston C' and as the area of this piston is substantially greater than the 40 area of the front of the pellet the pellet moves forward. The suction holes h leading from the forward end of the cylinder H into the rear groove a^6 of the body A assist in the action by reducing the pressure 45 in front of the piston C'. As soon as the pellet has moved forward into position ready for firing, the centrifugal balls c , which are thrown outwardly by the rotation 50 of the shell, enter the annular groove h' in the wall of the cylinder H', locking the pellet in its forward position.

Two set back pins D, D' are shown in the construction illustrated, but a single pin could be employed to hold both the ball d' 55 and the centrifugal pin d^3 .

If now the shell with the fuse in its sensitive condition strikes any obstruction, for example, the fabric of an airship, which while offering only a minute resistance to 60 the passage of the shell blocks up the free entry of air through the hollow striker B into the cylinder J, the pressure at the back of the striker piston B' is immediately reduced and the rearward air pressure on the 65 striker and the striker head (with any add-

ed pressure due to the obstruction) instantly moves back the striker and causes the firing pin b^3 to fire the detonator, igniting the charge f' in the magazine F through the flash hole f^2 . 70

If for any reason the sensitive impact fuse does not detonate the shell is exploded by the fixed time or delay action fuse E on which the sensitive fuse is mounted, but the fixed time fuse forms no part of the present invention and is shown merely to complete the illustration of the fuse construction. On discharge of the shell from the gun the pellet G' of the delay action fuse flies back against the striker G and the 80 fuse composition f is ignited.

What I claim and desire to secure by Letters Patent of the United States is:—

1. In a shell fuse of the kind set forth, a striker, a detonator pellet and means, under 85 the control of air pressure due to the flight of the shell, whereby both the striker and the pellet are caused to move forwardly from safety position into position for firing on impact. 90

2. In a shell fuse of the kind set forth, a striker, a detonator pellet, piston members on the striker and the pellet and cylinders receiving the said piston members, which cylinders are open, behind the respective 95 pistons, to air pressure due to the flight of the shell, whereby both the striker and the pellet are caused to move forwardly from safety position into position for firing on impact. 100

3. In a shell fuse as claimed in claim 1, an external head of mushroom form mounted on the outer end of the striker, which head is provided with a number of holes to reduce the area subjected to air pressure during 105 flight.

4. In a shell fuse of the kind set forth, a striker situated at the forward end of the fuse and provided with a mushroom head following the contour of the nose of the fuse, 110 a detonator pellet situated behind the striker and means, under the control of air pressure due to the flight of the shell, by which the striker is first moved forwardly so that the head projects clear of the nose of the shell 115 and the detonator pellet is caused to follow up the movement of the striker, whereby both striker and pellet are brought into sensitive position for firing on impact. 120

5. In a fuse of the kind set forth, a striker and a detonator pellet both provided with pistons and both adapted to take up a rearward and a forward position, a pair of cylinders in the fuse body receiving the said pistons and air pressure channels leading 125 from the front of the fuse to the said cylinders behind their respective pistons, for the purpose specified. 130

6. In a fuse as claimed in claim 5, means for holding the detonator pellet in its for-

ward position behind the striker after displacement of the pellet and striker into position for firing on impact.

7. In a fuse of the kind set forth, a pair of cylinders in the fuse body, a striker and a detonator pellet both provided with pistons adapted to be displaced under air pressure due to flight of the shell from the rear to the forward part of the said pair of cylinders; 5 a set back pin or pins holding the striker and pellet in rearward inoperative position, an air passage through the striker into the space behind the striker piston and an air passage from the said space to the cylinder 10 space behind the pellet piston, the fuse being

adapted on discharge of the shell to cause the set back pin or pins to release both the striker and pellet, whereupon the air pressure due to the flight of the shell acts on the striker piston to move the striker forward and then 20 acts on the pellet piston to cause the pellet to follow up the striker, for the purpose specified.

8. In a fuse as claimed in claim 2, rearwardly directed external channels in the 25 fuse body and air suction passages leading from the said cylinders in front of the piston members into the said external channels, for the purpose specified.

OWEN DAVID LUCAS.
